DESIGN FOR AN IRONING MACHINE CABINET

John A. Castricone, Peoria, Ill.

Application July 13, 1936, Serial No. 63,820

Term of patent 14 years

To all whom it may concern:

Be it known that I, John A. Castricone, a citizen of the United States, residing at Peoria, in the county of Peoria and State of Illinois, have invented a new, original, and ornamental Design for an Ironing Machine Cabinet, of which the following is a specification, reference being had to the accompanying drawing, forming part thereof.

The figure is a perspective view of an ironing machine cabinet, showing my new design, the other side of which is similar in appearance.

I claim:

The ornamental design for an ironing machine cabinet, as shown, and described.

JOHN A. CASTRICONE.
